UNITED STATES PATENT OFFICE.

JOHN C. STEWART, OF THE UNITED STATES ARMY, ASSIGNOR OF ONE-HALF
TO ANDREW S. BURT, OF THE UNITED STATES ARMY.

SOUNDING MECHANISM FOR TELEGRAPH-OFFICES.

SPECIFICATION forming part of Letters Patent No. 717,046, dated December 30, 1902.

Application filed March 18, 1902. Serial No. 98,807. (No model.)

To all whom it may concern:

Be it known that I, JOHN C. STEWART, of the United States Army, now located at Fort Myer, Virginia, have invented certain new and useful Improvements in Sounding Mechanism for Telegraph-Offices; and I do hereby declare the following to be a full, clear, and exact description of the same, reference being had to the accompanying drawings, forming part of this specification, and to the letters of reference marked thereon.

This invention relates to improvements in mechanism whereby the signals transmitted over a line-wire between telegraph offices or stations are rendered audible, so as to be interpreted or read by the receiving operator located at such offices or stations, the objects of the invention being to provide a simple and efficient apparatus capable of application to the plants at present installed, including, where necessary, the ordinary relay instruments and avoiding the necessity of employing local batteries and circuits such as are now usually employed for the amplification of the signals transmitted over the line-wires.

In carrying the invention into practice compressed air is employed as the motive power for operating suitable sounding mechanism, the application or control of the compressed air being effected through the instrumentality of a suitable valve mechanism under the control of the line-circuit—as, for instance, through the ordinary relay now employed for controlling the local circuit in which the ordinary sounder is located.

One of the main objects of the present improvement is to provide a mechanism which shall be capable of adaptation to conditions existing in any ordinary office or station plant and whereby the relays and sounders found in said stations or plants may, where desired, be utilized or employed as at present, but without the necessity of employing local circuits.

To the above ends the invention consists in certain novel details of construction and combinations and arrangements of parts, all as will be hereinafter described, and pointed out particularly in the appended claims.

Referring to the accompanying drawings, Figure 1 is a diagrammatic representation of

two stations or offices with a single line connecting the same. Fig. 2 is a longitudinal section, with parts broken away and in elevation, of a relay instrument with a sounder-controlling mechanism embodying the present improvements; and Fig. 3 is a section at right angles to Fig. 2, showing the sounder itself, together with its operating devices. Fig. 4 is a top plan view of the armature, showing the manner of supporting the same from the slide-valve.

Like letters of reference in the several figures indicate the same parts.

Referring particularly to Fig. 1, the letter A indicates a line-wire, and B B' stations connected by said line-wire. At each station an ordinary relay-magnet C is provided, said magnet being included directly in the line-circuit, which circuit also preferably includes the usual key or sounding instrumentality, such as indicated at D. In lieu of the usual local circuit, which is controlled by the relay-magnet C at each station, said magnet in accordance with the present invention controls 75 a valve and the latter controls the admission of pressure from a suitable source to a motor for operating the sounder. Pneumatic controlling devices are indicated in Fig. 1 by the letter E, pressure being supplied from a main F, to which as many instruments as desired may be coupled, said main leading to a suitable pressure-tank or generating apparatus—such, for instance, as the tank G and pump G'.

By reference to Figs. 2 and 3 it will be seen that the relay-magnet C is of usual construction and provided with the usual adjustments whereby it may be moved toward or from its armature H; but said armature H instead of being connected with controlling lever or switch for a local circuit is now directly connected with a slide-valve I, working through an adjustable housing K, with the upper end of which the pressure-main F communicates through a flexible pipe and coupling F'. The housing K is in turn supported on an adjustable cylinder L, preferably made adjustable by being threaded into a base M and held in its adjusted position by a lock-nut M'. Thus by the adjustment of the cylinder L and housing K or one of them the

armature H, mounted on the slide I, may be brought to the proper level for coöperation with a relay-magnet of any ordinary type, even though the relays found in the offices 5 to be installed vary widely in construction or size. The slide I is a valve which controls the admission of pressure from the housing K into the cylinder L and from the latter to exhaust, for which purposes the ports i i' are 10 formed in the slide I and coöperating ports i^2 and i^3 are formed in the housing. Thus when the ports i and i^2 register pressure will be admitted from the housing K into the cylinder L, and when the ports i' and i^3 register 15 pressure will be exhausted from the cylinder L to the atmosphere, and said ports are so arranged that when the armature H is in proximity to the poles of the relay-magnet pressure will be admitted to the cylinder L, this 20 position being the normal position of the instruments with the line-circuit completed.

Working in the cylinder L is a piston O, preferably having a projection o on its lower side adapted to bear on a lever P, rigidly but 25 adjustably attached to a sounder arm or lever Q. This arm or lever Q forms a part of a sounder Q' of ordinary construction, and therefore need not be specifically described. The adjustable connection between the lever 30 P and the sounder-lever Q is preferably formed by the post P', fastened in the lever Q and passing through the lever P, with set or lock nuts P^2 above and below the lever P, whereby it may be rigidly secured in any de- 35 sired position of adjustment and so as to adapt the structure for application to ordinary sounders of widely-different types. The adjustment of the cylinder L further facilitates the application of the device to 40 sounders of differing construction, as will be readily understood by those skilled in the art.

The connection between the armature H and the slide I is preferably formed as an adjustable connection by passing the thread 45 end of the slide I through the opening ordinarily found at the center of the armature and mounting lock-nuts H' on the opposite sides of the armature, as shown clearly in Fig. 2. The range of movement of the slide 50 is preferably controlled by adjustable stops I', mounted directly on said slide and capable of adjustment thereon through the medium of screw-and-slot connections, as shown.

The slide I is adapted to be moved in op- 55 position to the attraction of the relay-magnet C by the spring R, preferably adjustably connected with its post R' by a screw R^2 or other usual or convenient means for accom- plishing the same end.

60 The cylinder L, together with its base M and the sounder Q', are usually mounted on an ordinary metallic base S, which latter is in turn carried by a wooden base T, lag-screws being employed for uniting the parts, 65 and the relay is also preferably mounted on the base, as is customary in electrical equipments of this character.

In operation the relay-magnet C normally holds the valve in the position indicated in Fig. 2, and air-pressure supplied through the main is admitted by said valve to the cylinder L, depressing the piston O and holding the sounder arm or lever Q depressed. Upon an interruption of the main-line circuit the relay-magnet C releases the armature H, when 70 the valve I under the influence of its spring R cuts off the air-pressure and opens the exhaust-ports i' and i^3 , permitting the pressure in the cylinder L to escape and the sounder lever or arm to rise under the influence of its compression-spring U, thereby 75 giving the customary reverse click of a sounding instrument. Upon the circuit being again established the piston is driven down by the air admitted to the cylinder and the 80 direct click or audible sound is given by the sounder, due to the fact that the sounder arm or lever is suddenly depressed by the piston. In order to avoid any false sound 85 which might occur between the piston and lever P, a leather, rawhide, or non-resonant insert V may be interposed between these parts, as shown in Fig. 3, thereby deadening any sound which might be occasioned by the contact at this point and insuring an 90 audible signal corresponding to the audible signals emanating from an ordinary sounder.

From the foregoing it will be seen that an operator accustomed to the reading of signals of an ordinary sounder will be able to 95 read the signals from the present sounder with his customary alacrity and the air-pressure may be made sufficient to give a very 100 loud signal—in fact, much louder than can be obtained by the use of ordinary local batteries and magnets. Furthermore, in large 105 offices or where a number of sounders are to be installed the saving in the cost of the local batteries and maintenance of plant is ma- 110 terially lessened, particularly in those offices where it is now the practice to employ pneumatic-despatch tubes requiring air-pressure- 115 creating devices, which may be availed of for supplying air under pressure to operate the sounders.

Having thus described my invention, what I 115 claim as new, and desire to secure by Letters Patent, is—

1. The combination with a relay-magnet and a sounder of a telegraph-station plant, of a pneumatically-operated motor mechanism for the sounder, a valve for controlling said pneumatically-operated motor mechanism and an armature for the relay-magnet supported directly by said valve; substantially 120 as described.

2. In a telegraph-station plant, the combination with a relay-magnet and sounder, of a pneumatically-operated motor mechanism for the sounder, a reciprocatory valve controlling the said motor mechanism, a spring for moving said valve in one direction and an armature mounted directly on said valve in position to coöperate with the relay-mag- 125 130

net for moving the valve in the opposite direction, substantially as described.

3. In a telegraphic-station plant, the combination with a relay-magnet, of a pneumatically-operated motor embodying a cylinder and vertically-adjustable valve, an armature carried by said valve in position to coöperate with the relay-magnet and a sounder operated by said motor; substantially as described.

10 4. In a telegraphic-station plant, the combination with a relay-magnet and sounder, of a pneumatically-operated motor embodying a slide-valve controlled by the relay-magnet, adjustable stops for limiting the movement 15 of said valve and connections between said motor and the sounder; substantially as described.

5. In a telegraphic-station plant, the combination with a relay-magnet and a sounder, 20 of a pneumatically-operated motor controlled by the relay-magnet and embodying a vertically-disposed cylinder, a piston working in said cylinder with connections between said piston and sounder-arm and a valve controlling the admission and exhausting of pressure 25 to and from said cylinder; substantially as described.

6. In a telegraphic-station plant, the combination with a relay-magnet and a sounder, 30 of a pneumatically-operated motor controlled by the relay-magnet and embodying a verti-

cally-adjustable cylinder, a piston working in said cylinder with connections between said piston and sounder-arm and a valve controlling the admission and exhausting of pressure 35 to and from said cylinder; substantially as described.

7. In a telegraphic-station plant, the combination with a relay-magnet and sounder, of a pneumatically-operated sounder-motor embodying a valve controlled by the relay-magnet, a piston and a non-resonant material interposed between the piston and sounder-arm; substantially as described.

8. In a telegraphic-station plant, the combination with the relay-magnet and sounder, of a pneumatically-operated motor for the sounder and controlled by the relay-magnet, said motor embodying a vertically-disposed cylinder containing an operating-piston, a 50 housing superimposed on said cylinder and detachably connected therewith, a slide-valve working through said housing for controlling the admission and exhausting of pressure to the cylinder and an armature for the relay- 55 magnet connected with said valve; substantially as described.
